(57) CLAIM

The ornamental design for a shoe upper, as shown and described.

DESCRIPTION

FIG. 1 is a top perspective view of a shoe upper showing my new design;

FIG. 2 is a right side view of the shoe upper shown in FIG. 1;

FIG. 3 is a left side view of the shoe upper shown in FIGS. 1-2;

FIG. 4 is a top plan view of the shoe upper shown in FIGS. 1-3.

FIG. 5 is a frontal view of the shoe upper shown in FIGS. 1-4; and,

FIG. 6 is a rear view of the shoe upper shown in FIGS. 1-5. The broken line drawing of a strap anchor section, and shoe sole in FIGS. 1-6 is for illustrative purposes only and forms no part of the claimed design.
